COMBINED CONTAINER AND STORAGE BIN

Clarence B. Coleman and Harry R. Kattelmann, Oakland,
Calif., assignors to Fabricated Metals, Inc.

Filed Mar. 25, 1971, Ser. No. 128,231

Term of patent 14 years

Int. Cl. D23—01

U.S. Cl. D23—2

FIG. 1 is a top plan view of a combined container and storage bin embodying our invention;

FIG. 2 is a side elevation thereof;

FIG. 3 is a front elevational view thereof;

FIG. 4 is a bottom plan view thereof; and

FIG. 5 is a front elevational view of a modified form of the container and storage bin shown in FIG. 1, the modification being the change in the cover guard.

We claim:

The ornamental design for a combined container and storage bin, as shown and described.
